UNITED STATES PATENT OFFICE.

ORLA E. WEIDNER, OF ARCOLA, ILLINOIS.

INTERNAL-COMBUSTION ENGINE.

1,117,938.

Specification of Letters Patent. Patented Nov. 17, 1914.

Application filed May 21, 1914. Serial No. 310,010.

To all whom it may concern:

Be it known that I, ORLA E. WEIDNER, a citizen of the United States, residing at Arcola, in the county of Douglas and State of Illinois, have invented certain new and useful Improvements in Internal-Combustion Engines; and I do declare the following to be a full, clear, and exact description of the invention, such as will enable others skilled in the art to which it appertains to make and use the same.

This invention relates to internal combustion engines and more particularly to the class of engines of two-cycle explosive type in which the explosive mixture is first compressed before ignition.

The object of the invention is to provide simple and efficient means for injecting the explosive mixture into the combustion chamber and which will operate to thoroughly clean the combustion chamber of dead or spent gases whereby a thorough carburation of the explosive chamber is obtained.

With the above and other objects in view, the invention consists of certain novel features of construction, combination and arrangement of parts as will be more fully described and claimed.

In the accompanying drawings: Figure 1 represents a vertical sectional view of an engine constructed in accordance with this invention and with the piston at its extreme limit of its compression stroke; Fig. 2 is a similar view with the piston at the limit of its working stroke.

In the embodiment illustrated, a cylinder 1 is shown having an enlarged lower portion 2 and in which a correspondingly shaped piston 3 is designed to operate and between the laterally extending shoulders 2' and 3' of said cylinder and piston is formed a combustion chamber 4 having the usual sparking plug 5 extending therewith near the upper end of the combustion chamber. The piston 3 is made hollow with a transverse partition 6 spaced a suitable distance from its outer end to form a gas receiving piston chamber 7. This chamber 7 has an opening 8 in one side wall adjacent the partition 6 for a purpose to be described. At the upper or outer end of the reduced portion of the cylinder 1 which constitutes the compression chamber, is formed a by-pass 9 designed to cooperate with the opening 8 in the piston chamber at predetermined intervals as will be hereinafter described.

The compression cylinder 1' is provided intermediately of its ends with an inlet 10 for the explosive mixture which inlet communicates with a carbureter 11 of any suitable construction.

The inner portion 2 of the cylinder 1 which constitutes the combustion chamber is provided near its lower end with an exhaust port 12 for the spent gases.

The piston 3 is provided with suitable seats 13 in the periphery of its larger portion to receive packings for insuring a fluid tight connection between this portion of the piston and the walls of the combustion cylinder such as are usually employed in apparatus of this character. The smaller and larger portions of the cylinder 1 which form the compression and combustion cylinders, may be made integral as shown or rigidly connected in any suitable manner. The double integral piston is machined to fit both of said cylinders and the opening 8 of the chamber 7 at the outer end of said piston is positioned to register with the lower end of the by pass 9 when the piston is at or near the extreme limit of its compression stroke as shown in Fig. 1 and to register with the combustion chamber 4 when said piston is at the limit of its working stroke as shown in Fig. 2. A piston pin connection 14 is shown clamped into place on the inside of the piston and a packing groove 13' is arranged near the lower end of the compression cylinder to receive a packing to prevent leakage from the lower cylinder into the upper.

In the use of this engine, when the piston 3 is at the limit of its inward or working stroke as shown in Fig. 2, all of the exhaust or spent gases have been forced out through the exhaust port 12 and the explosive mixture from the carbureter 11 rushes into the compression cylinder above the piston 3 because of the vacuum which is formed in said cylinder by the inward stroke of the piston. Then as the piston moves outward, this mixture is compressed between the outer end of the compression chamber and the outer end of the piston until the piston nearly reaches the limit of its outer stroke when the auxiliary inlet port 8 is brought into communication with the by-pass 9 and the gas in the compression chamber rushes into the piston chamber 7 and when the piston moves inward into the position shown in Fig. 2, the auxiliary inlet 8 registers with the combus-

tion chamber 4 and the compressed gas in the piston chamber rushes out into the combustion chamber forcing out the exhaust or spent gases and is again compressed in the 5 combustion chamber on the outer stroke of the piston and is fired in the ordinary manner by the sparking plug which is so timed for this purpose. As this operation must be repeated at each revolution or double 10 stroke of the piston, it produces a two stroke or two cycle engine and because of the packings of the cylinders and the absence of crank case compression, it is obvious that this engine may be used as a rotary motor.

15 I claim as my invention:

1. In an internal combustion engine, the combination of a cylinder having a smaller axial extension forming a compression chamber, a piston working in said cylinder 20 and provided with an axial extension working in the compression chamber, the outer end of said compression chamber having a by-pass formed therein, a chamber formed in the outer end of said piston and having 25 a passage positioned to register with said by-pass when the piston is nearing the limit of its compression stroke and for registering with the combustion chamber when it nears the limit of its working stroke.

30 2. In an internal combustion engine, the combination of a cylinder having an axial extension of less diameter forming a compression chamber, of a power piston fitting the cylinder and having an axial extension fitting the compression chamber, said piston 35 being hollow and provided near its outer end with a transverse partition forming a

gas receiving chamber, said gas receiving chamber having an opening in one side wall thereof, the compression chamber being provided near its outer end with a by-pass adapted to register with the opening in the piston chamber when the piston nears the limit of its compression stroke, said opening being also positioned to register with the 45 combustion chamber when the piston nears the limit of its working stroke.

40 3. In an internal combustion engine, the combination of a cylinder having an axial extension of less diameter forming a compression chamber, of a power piston fitting the cylinder and having an axial extension fitting the compression chamber, said piston being hollow and provided near its outer end with a transverse partition forming a 45 gas receiving chamber, said gas receiving chamber having an opening in one side wall thereof, the compression chamber being provided near its outer end with a by-pass adapted to register with the opening in the 50 piston chamber when the piston nears the limit of its compression stroke, said opening being also positioned to register with the combustion chamber when the piston nears the limit of its working stroke, and a piston 55 pin connection clamped into position on the inside of said piston.

60 In testimony whereof I have hereunto set my hand in presence of two subscribing witnesses.

ORLA E. WEIDNER.
